US00D964390S

(12) **United States Design Patent** (10) Patent No.: **US D964,390 S**
 Mairs et al. (45) Date of Patent: ** Sep. 20, 2022

(54) **DISPLAY SCREEN OR PORTION THEREOF WITH A GRAPHICAL USER INTERFACE**

(71) Applicant: **INSPIRE MEDICAL SYSTEMS, INC.**, Golden Valley, MN (US)

(72) Inventors: **Nicholas Mairs**, Minneapolis, MN (US); **Brody Belland**, St. Louis Park, MN (US); **John Rondoni**, Plymouth, MN (US); **Donovan Fellows**, Lake Elmo, MN (US); **Kathleen Tolmie**, Mendota Heights, MN (US)

(73) Assignee: **INSPIRE MEDICAL SYSTEMS, INC.**, Golden Valley, MN (US)

(**) Term: **15 Years**

(21) Appl. No.: **29/771,461**

(22) Filed: **Feb. 23, 2021**

(57) **CLAIM**

The ornamental design for a display screen or portion thereof with a graphical user interface, as shown and described.

DESCRIPTION

The sole FIGURE is a front view of a display screen or portion thereof with a graphical user interface showing our new design.

The outermost broken lines show a display screen or portion thereof and form no part of the claimed design. The remaining broken lines show elements of the graphical user interface that form no part of the claimed design.
